UNITED STATES PATENT OFFICE.

OLEAUS ARSENAULT, OF WEBSTER, MASSACHUSETTS, ASSIGNOR OF ONE-HALF TO
ARTHUR C. POTTER, OF WEBSTER, MASSACHUSETTS.

BLOW-OUT PATCH.

Application filed November 10 1927. Serial No. 232,439.

This invention relates to a patch for repairing tires, particularly for blowouts.

The principal objects of the invention are to provide a patch for this purpose which 5 includes a sheet of material to reinforce the inner tube and another sheet of material to stand the wear on the outside, said sheets being separate and both being very flexible to constitute a yielding cushion; to provide 10 a patch which will not crack and will have a greater durability than the patches now on the market; to provide a patch having an air space that will prevent heating and friction and provided with a fabric between 15 the two surfaces that have been mentioned for strengthening the patch and connecting it with the end flaps by which it can be handled and also held in position in the tire. This patch contains nothing that will chafe 20 the inner tube on account of the flexibility of the inner surface thereof and the freedom of the fabric and outer layer of the rubber.

Other objects and advantages of the invention will appear hereinafter.

Reference is to be had to the accompanying drawings in which

Fig. 1 is a plan of a preferred form of patch, constructed in accordance with this 30 invention, laid out flat;

Fig. 2 is a sectional view of same on the line 2—2 in Fig. 1; and

Fig. 3 is a transverse sectional view of 35 a tire with a blow-out and with this patch applied in place therein.

The patch is used very largely in the way now understood in the art, but it is formed of three layers. The piece of cotton fabric 10 extends throughout the area of the patch 40 proper and beyond it at its two ends to provide two flaps 11 for use in handling it and adapted to be bent over to hold it in position after it is applied.

On each side of the cotton fabric 10 is 45 placed a layer 12 and 13 of new soft flexible live rubber. These are both cemented hermetically to the opposite surfaces of the cotton fabric 10 all round the edges and preferably in registration with each other. They 50 are left entirely free from the cotton fabric throughout all their central area which leaves a thin air space on each side of the fabric and inside each rubber piece. This constitutes a flexible cushion. The air in- 55 side, when it becomes heated, will expand

and make the patch even more flexible than when it is in a cool state.

In placing the patch in position it is grasped by the two flaps 11 and pulled over the blowout into place. These flaps are 60 turned back if they reach far enough and held in position in the space inside the outer shoe. Otherwise the fixing of the patch in position is the same as the ordinary practice.

In use, it will be seen that on the outer 65 side of the patch there is a layer of live rubber 13 having an air space behind it which makes it durable when subjected to external wear. On account of the flexibility of the rubber and the air cushion behind it it does 70 not wear like an ordinary piece of rubberized fabric. If it gets punctured or worn so as to allow the air in this air space to escape there is an air space behind it on the other side of the cotton fabric 10 which 75 still gives it a cushion effect. This layer can be forced by the air pressure out into the hollow or crack in the outer shoe to a large extent without subjecting the inner 80 layer 12 of rubber, which is secured to the inner tube, to the external wear, as is common in this industry.

Even if both layers of rubber are forced outwardly the inner one is always protected by the outer one and by the cotton fabric 85 as long as they last. The patch is much more durable than an ordinary patch on account of this feature and also on account of the two layers of rubber to penetrate instead of one.

The cotton fabric extends throughout the entire area of the patch proper and affords a flexible, but non-stretchable, foundation for the whole patch and keeps the two rubber layers from being stretched or misplaced 95 except throughout the space just inside their areas and even that space is restricted in this respect. The two end flaps are integral with the central sheet of fabric so that any force applied to them is not transmitted 100 directly to the rubber layers as they are merely surface layers on the cotton fabric. The rubber part of the patch cannot be injured by stress applied to these two ends, unless it is great enough to tear the cotton 105 duck.

This patch is soft and flexible. It will not crack under ordinary circumstances. It provides a patch on the inside and the air space between the two rubber layers pre- 110

vents heating and friction. There is nothing about it to wear down and chafe the inner tube as it works back and forth thereon in use.

5 Although I have illustrated and described only a single form of the invention I am aware of the fact that modifications can be made therein by any person skilled in the art without departing from the scope of the 10 invention as expressed in the claims.

Therefore I do not wish to be limited to all the details of construction herein shown and described, but what I do claim is:—

15 1. As an article of manufacture, a blow-out patch comprising two sheets of live rubber cemented hermetically around their edges and having an air space between them for the purpose described.

20 2. As an article of manufacture, a tire patch comprising a center layer of non-stretchable flexible fabric and a layer of live rubber cemented on each side thereof around the edges of said layers with the

center free to form an air space between 25 said edges on each side of the fabric.

3. As an article of manufacture, a tire patch comprising a sheet of cotton fabric having its ends free for use in handling and securing the patch in position and provided with a layer of rubber on each side thereof, 30 the fabric projecting beyond the rubber and providing means for handling the patch, and the patch having an air space between the two layers of rubber.

4. As an article of manufacture, a tire 35 patch comprising a layer of non-stretchable fabric adapted to be mounted on the outside of the inner tube and a layer of rubber on the exterior thereof hermetically cemented at its edges and sealed, leaving an air space 40 or cushion between the fabric and outer layer of rubber to receive directly the wear from friction of the shoe on the road bed.

In testimony whereof I have hereunto affixed my signature.

OLAUS ARSENAULT.
